CLAIM

The ornamental design for a pillow cover, as shown and described.

DESCRIPTION

The file of this patent contains at least one drawing executed in color. Copies of this patent with color drawing will be provided by the Office upon request and payment of the necessary fee.

FIG. 1 is a front elevation view of a pillow cover, showing the new design; and,

FIG. 2 is a rear elevation view thereof.

The parts of the design having the broken line perimeter of even length shown in FIGS. 1 and 2 illustrate portions of the duvet that form no part of the claimed design.

1 Claim, 2 Drawing Sheets(1 of 2 Drawing Sheet(s) Filed in Color)(56)
